UNITED STATES PATENT OFFICE

2,520,503

ELECTRIC LIGHT UNIT FOR USE IN CONNECTION WITH SWIMMING

Harold W. Henning, Jr., Naperville, Ill.

Application September 24, 1948, Serial No. 51,086

3 Claims. (Cl. 240—59)

1

The present invention relates generally to electric light units. More particularly the invention relates to that type of unit which is used for effecting illumination and as its components or parts comprises a dry cell battery, a conventional electric socket with an electric incandescent lamp therein, and a pair of single lead flexible electric conductors, one of which extends between, and is connected to, the exposed end of the carbon rod of the battery and one of the contacts of the socket and the other of which extends between, and is connected to, the zinc shell of the battery and the other contact of the socket.

One object of the invention is to provide an electric light unit of this type which is adapted, together with a group of like units, to be worn by a swimmer in connection with an aquatic exhibition and operates, when lighted while the wearer is swimming, to produce an ornamental and attractive optical effect.

Another object of the invention is to provide an electric light unit of the type and character under consideration which embodies as an attaching medium or instrumentality therefor a strip of adhesive tape, the central portion of which partially surrounds, and is adhesively connected to, the central portion of the dry cell battery and the ends of which are free in order that they may be pressed into adhering relation with any desired part of the body of the wearer, such, for example, as an arm or a leg.

Another object of the invention is to provide an electric light unit of the aforementioned type in which the lamp carrying socket extends transversely and is spaced a small distance from the central portion of the dry cell battery and the flexible electric conductors are substantially the same in length and are connected to opposite ends of the battery to the end that when the battery is positioned crosswise of the direction of swim of the wearer they permit the lamp carrying socket to swing laterally into a trailing position wherein it offers minimum resistance to passage of the unit through the water and hence does not impede swimming on the part of the wearer regardless of whether the wearer is swimming in a forward or rearward direction.

A further object of the invention is to provide an electric light unit of the last mentioned character in which the dry cell battery and the flexible electric conductors are provided with coatings of pliable, water resistant insulating material, such as paraffin, in order to prevent short

2

circuiting of the unit in connection with underwater use thereof.

A still further object of the invention is to provide an electric light unit which effectively and efficiently fulfills its intended purpose, may be produced at a comparatively low cost and occupies but a small amount of space.

Other objects of the invention and the various advantages and characteristics of the present light unit will be apparent from a consideration of the following detailed description.

The invention consists in the several novel features which are hereinafter set forth and are more particularly defined by claims at the conclusion hereof.

The invention consists in the several novel features which are hereinafter set forth and are more particularly defined by claims at the conclusion hereof.

In the drawing which accompanies and forms a part of this specification or disclosure and in which like numerals of reference denote corresponding parts throughout the several views:

Figure 1 is a perspective view of an electric light unit embodying the invention;

Figure 2 is a side view, partly in side elevation and partly in section, illustrating the construction and design of the various parts of the unit;

Figure 3 is an end view of the unit illustrating the manner in which the flexible electric conductors which lead to opposite ends of the battery permit the lamp carrying socket to swing laterally into a trailing position wherein it extends to one side or the other of the battery, depending upon whether the wearer is swimming forwards or rearwards; and

Figure 4 is a fragmentary front view of a swimmer wearing a group of units embodying the invention.

The electric light unit which is shown in the drawing constitutes the preferred form or embodiment of the invention. It is adapted, as hereinafter described more in detail, to be worn on the body, legs or arms of a swimmer while the latter is engaged in swimming operations and functions when illuminated to produce an attractive optical effect. As its parts or components the unit comprises a dry cell battery 5; a strip of tape 6; an electric socket 7; an incandescent lamp 8; and a pair of conductors 9 and 10. Due to its particular construction or design the unit is capable of being immersed in the water while in an illuminated condition.

The battery 5 is of conventional or standard construction and consists of a cylindrical zinc

shell 11 and a carbon rod 12. Preferably the battery 5 is in the form of a small sized flash-light battery. The zinc shell 11 has one end thereof open and consists of a cylindrical side wall and a circular end wall. The carbon rod 12 is disposed centrally within the shell and is arranged so that one end thereof projects through the open end of the shell. The space between the rod and the shell is filled with a depolarizing agent and an exciting compound, as well understood in the art. The cylindrical side wall of the shell is surrounded by a cardboard tube 13 for protective purposes. It is contemplated that in connection with use of the unit the dry cell battery 5 will be worn by the wearer in such a position that it extends crosswise of direction of swim. For example, if the unit is worn on the leg, as shown in Figure 4 of the drawing, the battery will be positioned so that it extends transversely of the leg.

The strip 6 of adhesive tape serves as a medium or instrumentality for attaching the unit to the wearer. It is preferably in the form of a length of surgical tape of the type that comprises a fabric backing and a coating of permanently tacky, pressure sensitive adhesive on the under or bottom face of the fabric base, as shown in Figures 1 and 3 the central portion of the strip 6 is applied to the central portion of the cardboard tube 13 so that it extends more than half way therearound. The adhesive coating of the strip serves to hold the central portion of the strip in adhering relation with the central portion of the cardboard tube 13. The ends of the strip 6 are bent or folded so as to extend outwards in opposite directions and form, in effect, tabs which are adapted to be pressed into adhesively connected relation with any exposed part of the body, legs or arms of the wearer of the unit. It is contemplated that the strip 6 of adhesive tape will form a more or less permanent part of the unit. In attaching the unit the dry cell battery 5 is first placed against the desired exposed part of the wearer's body, legs or arms and then the tab forming ends of the adhesive strip 6 are pressed inwards so as to cause the adhesive coating thereon to adhere to the wearer's skin. When the ends of the strip 6 are pressed firmly in place the strip serves securely but releasably to hold the unit in place.

The electric socket 7 is of the type that is used in connection with Christmas tree lights. It consists of a cup shaped member 14 of insulating material, an internally threaded tubular member 15, and a pair of contacts 16 and 17. The cup shaped member 14 consists of a continuous side wall and a centrally apertured bottom wall and is open at its outer end. The internally threaded tubular member 15 is fixedly secured within the continuous side wall of the cup shaped member 14 and is provided at its inner end with the contact 16. The other contact, i. e., the contact 17, is mounted on the bottom wall of the cup shaped member 12 in spaced relation with the contact 16. As shown in the drawing the electric socket 7 extends transversely of the dry cell battery 5 and is disposed midway between the ends of the battery and a small distance from the central portion of the battery. It is in radial alignment with the central portion of the strip 6 of adhesive tape and is positioned or arranged so that the open end of the cup shaped member 14 faces outwards. As hereinafter described the conductors 9 and 10 serve electrically to connect the socket 7 to the battery 5 and also to hold the socket in its proper operative position with respect to the battery.

The incandescent lamp 8 is of the type that is used in a flashlight and consists of a bulb 18 and a plug 19 at one end of the bulb. The bulb houses a filament 20 and is suitably connected to one end of the plug. The plug has a contact 21 at its outer end and is surrounded by an externally threaded jacket 22 whereby it may be secured in connected relation with the electric socket 7. The contact 21 is connected to one end of the filament 20 and is adapted when the lamp is connected to the socket to engage the contact 17. The externally threaded jacket is formed of any suitable electric conducting material. It is connected to the other end of the filament and when the lamp is connected to the socket contacts the internally threaded tubular member 15 of the socket.

The conductors 9 and 10 are flexible but somewhat stiff. Each consists of a single wire and a tubular sheath therefor. As best shown in Figures 1 and 2 the conductors 9 and 10 are the same in length and the conductor 9 has one end thereof soldered or otherwise fixedly secured to the usual metal cap on the outer or exposed end of the carbon rod 12 of the dry cell battery 5. The other end of the conductor 9 leads through the aperture in the bottom wall of the cup shaped member 14 of the socket 7 and is soldered to the contact 17 which, as hereinbefore pointed out, engages the contact 21 on the outer end of the lamp plug when the lamp is in connected relation with the socket 7. The conductor 10 has one end thereof soldered or otherwise fixedly secured to the circular end wall of the zinc shell 11 of the battery 5. The other end of the conductor 10 leads through the aperture in the bottom wall of the cup shaped member 14 of the socket and is soldered to the contact 16 on the inner end of the internally threaded tubular member 15 of the socket. The conductors 9 and 10 are bent inwards around the ends of the battery 5 and then are inclined toward one another so as to hold the socket 7 in spaced or centered relation with the battery. They are sufficiently flexible to permit the lamp carrying socket to swing laterally to one side or the other of the battery as shown in dotted lines in Figure 3. Normally the conductors will hold the lamp carrying socket in the position shown in full lines in Figure 3. When the unit is in use in connection with a swimming operation the conductors, due to their inherent flexibility or resiliency, permit the lamp carrying socket to swing laterally in a trailing position adjacent the flesh of the wearer, depending upon the direction in which the wearer of the unit is swimming. If the wearer of the unit is swimming forwards the lamp carrying socket swings rearwards into a position wherein it is substantially parallel to the flesh and hence offers but small resistance to the wearer's swimming. In the event that the wearer of the unit changes the direction of swim from forwards to backwards the lamp carrying socket swings throughout an arc of substantially 180° where it is again in trailing position so far as direction of swim is concerned.

In order to prevent short circuiting of the unit when it is under water in connection with use thereof the battery 5 and the conductors 9 and 10 are provided with coatings of any suitable pliable water repellent insulating material such as paraffin. The coatings are preferably applied before mounting of the attaching strip 6 into place and by immersing the battery and conductors in a body of melted paraffin or other ma-

terial and then withdrawing the battery and conductors and permitting the coatings thereon to dry.

When it is desired to use the unit as indicated the battery 5 is placed against the wearer's skin and is fastened in place by pressing the ends of the strip 6 of adhesive tape into adhering relation with the wearer's skin. As heretofore indicated the battery is preferably positioned so that it extends in a crosswise direction. When the unit is in place the lamp carrying socket 7 extends outwards at right angles to the ends of the strip 6 as shown in full lines in Figure 3. The unit is illuminated by securing the lamp 8 fully into the socket 7. In the event it is desired to turn out the lamp it is only necessary to loosen the lamp in the socket to such an extent as to move or shift the contact 21 out of engagement with the contact 17. When the unit is immersed in the water the lamp carrying socket, due to the action of the conductors 9 and 10, swings laterally forwards or backwards with respect to the battery, depending upon the direction in which the wearer is swimming.

The herein described electric light unit is essentially simple in design and may be constructed at a comparatively low cost. It effectively and efficiently fulfills its intended purpose and is capable of being applied and removed with facility.

The invention is not to be understood as restricted to the details set forth since these may be modified within the scope of the appended claims without departing from the spirit and scope of the invention.

Having thus described the invention what I claim as new and desire to secure by Letters Patent is:

1. As a new article of manufacture, an electric light unit adapted to be worn by a swimmer in connection with swimming and comprising a conventional unenclosed small sized flash-light variety dry cell battery adapted to be placed lengthwise against a part of the swimmer and embodying a metallic cup shaped shell and a rod disposed centrally within the shell and having one end thereof located adjacent the open end of said shell, a strip of flexible tape provided on its inner surface with a coating of pressure sensitive permanently tacky adhesive and having the central portion thereof extending part way around, and adhesively connected to, the battery and its ends free and adapted to be adhesively connected to said part of the swimmer, a lamp carrying socket positioned adjacent the battery and embodying a pair of contacts, and a pair of single lead conductors having certain ends thereof connected to the contacts of the socket and their other ends connected directly to the shell and said one end of the rod, said conductors being sufficiently long and flexible to support the socket so that it is capable of swinging relatively to the battery during use of the unit.

2. As a new article of manufacture, an electric light unit adapted to be worn by a swimmer in connection with swimming and comprising a conventional unenclosed small size flash-light variety dry cell battery adapted to be placed lengthwise against a part of the swimmer and embodying a metallic cup-shaped shell and a rod disposed centrally within the shell and having one end thereof positioned adjacent the open end of said

shell, a strip of flexible adhesive tape provided on its inner surface with a coating of pressure sensitive, permanently tacky adhesive and having the central portion thereof extending part way around, and adhesively connected to, the central portion of the battery and its ends free and adapted to be adhesively connected to said part of the swimmer, a lamp carrying socket extending transversely of the battery, positioned a small distance outwards of the central portion of said battery and provided with a pair of contacts, and a pair of substantially equal length, flexible, single lead conductors having certain ends thereof connected to the contacts of the socket and their other ends connected directly and respectively to the end wall of the battery shell and said one end of the rod, said conductors being sufficiently long and flexible to support the socket so that it is capable of swinging circumferentially with respect to the battery during use of the unit.

3. As a new article of manufacture, an electric light unit adapted to be worn by a swimmer in connection with swimming and comprising a conventional unenclosed small sized flash-light variety dry cell battery adapted to be placed lengthwise against a part of the swimmer and embodying a metallic cup-shaped shell with a cardboard tube therearound and a rod disposed centrally within the shell and having one end thereof disposed adjacent the open end of the shell, a strip of flexible tape provided on its inner surface with a coating of pressure sensitive, permanently tacky adhesive and having the central portion thereof extending part way around, and adhesively connected to, the central portion of the battery and its ends free and adapted to be adhesively connected to said part of the swimmer, a lamp carrying socket extending transversely of the battery, positioned a small distance outwards of the central portion of said battery and provided with a pair of contacts, a pair of substantially equal length, flexible, single lead conductors having certain ends thereof connected to the contacts of the socket and their other ends connected directly and respectively to the end wall of the battery shell and said one end of the rod, and serving to support the socket so that it is capable of swinging circumferentially with respect to the battery during use of the unit, a coating of pliable, water resistant, insulating material completely encasing and forming a part of said battery, and coatings of like material around said conductors.
